DETACHABLE VANE ASSEMBLY FOR CONTACT COLUMN

Filed Oct. 17, 1951

UNITED STATES PATENT OFFICE

2,649,291

DETACHABLE VANE ASSEMBLY FOR
CONTACT COLUMN

Ben Bartolucci, Chicago, Ill.

Application October 17, 1951, Serial No. 251,798

8 Claims. (Cl. 261—79)

1

The present invention relates generally to fractionating columns or the like, but more particularly to a novel and improved device which will more effectively cause a more intimate interaction between the descending liquids and the rising vapors or gases so as to set up in effect a dense centrifugal revolving cleansing liquid spray which will contribute to the efficient operation of the device.

A further object of the invention is to provide a plurality of vertically spaced apart detachable or removable unit or spirally arranged vane assemblies which can be individually removed for the purpose of cleaning or repair.

A still further object of the invention is to provide a novel vane unit or assembly in which the inner ends of the individual vanes are secured to a centrally disposed top circular disc and the lower outer edges of the vanes secured to an annular ring for rigidly securing the vanes together.

A further object of the invention is to provide a fractionating column in which the vane assemblies are suspended from annular collars by displaceable hangers.

A still further object of the invention is to provide a novel and improved fractionating column or the like in which a plurality of vane assemblies are supported in vertical axial alignment in spaced apart relation with respect to one another and at the same time are held spaced from the cylindrical wall of the casing.

These and other objects are accomplished by providing a construction and an arrangement of the various parts in the manner hereinafter described and particularly pointed out in the appended claims.

Referring to the drawings:

Fig. 1 is a side elevational view of my fractionating column or the like embodying the improvements of my invention;

Fig. 2 is a top plan view of the same;

Fig. 3 is an enlarged cross sectional view taken on the line 3—3 in Fig. 1;

Fig. 4 is an enlarged fragmentary cross sectional view showing the manner in which the removable vane units or assemblies are detachably supported within the casing;

Fig. 5 is a plan view of one of the blades of the vane assembly; and

Fig. 6 is an enlarged detailed view showing the manner of supporting and detachably locking the vane assemblies in position.

In illustrating one embodiment my invention may assume in practice, I have shown the same

2

as comprising a cylindrical casing or column, generally indicated by the reference character 10. The upper end of the casing is closed by a removable cover 12. Projecting laterally from the casing 10 is an air or gas outlet 14 which is positioned adjacent the upper end thereof. The lower end of the casing is connected to a funnel-like connection 16 which, in turn, is connected to a liquid discharge conduit 18. Extending tangentially with respect to the cylindrical casing 10 at a point adjacent the funnel 16 is an air or gas inlet 20.

One of the important features of the present invention involves the construction and detachability, as well as the positioning of a plurality of vane assemblies or units which more effectively secures intimate interaction and commingling between the descending liquid and the rising vapors or gases. These removable vane assemblies or units are generally indicated by the reference character 22, any number of which may be employed. These vane assembly units comprise a top disc 24 of relatively small diameter to which is secured the inner ends of a plurality of spirally arranged and substantially radially disposed blades or vanes 26. These individual blades are provided with steeply inclined surfaces 28 which lie in a position of approximately sixty to seventy degrees to a horizontal plane. Adjoining the surfaces 28 are gradually inclined surfaces 30 which are inclined to a horizontal plane at approximately twenty to twenty-five degrees. These surfaces are jointed together at a diagonal intersecting line 32 and form in effect the fluid deflecting surfaces for setting up a centrifugal and circuitous dispersion of the liquid in its downwardly flowing movement during the raising of the vapors and gases. Secured to the lower outer ends of each of the blades or vanes 26 adjacent the periphery thereof is an annular flat ring or washer 34 which not only performs the function of reinforcing and strengthening the detachable vane assembly or unit, but also performs a very essential function of securing a greater dispersion of the downwardly traveling liquid and also a more intimate interaction and commingling of the vapors and gases with the downwardly moving liquid. The ring or washer 34 is inclined inwardly and downwardly towards the center of the column as clearly shown in Fig. 4 of the drawings and discharges some of the liquid towards the center thereof while the upwardly flowing vapors or gases pass upwardly through the opening in the ring and deflects or sprays some of the liquid beyond the outer per-

riphery of the ring against the inner wall of the casing.

Secured in the axial center of each of the vane assemblies or units and preferably to the circular discs 24 is an eye 36 which is used for the purpose of inserting a rod with a hook on the end thereof for engagement with it for removing the units or vane assemblies in the manner hereinafter more fully described. Located in axially spaced relation with respect to one another are a plurality of annular collars 38 whose outer diameter snugly fit within the confines of the cylindrical casing 10 so as to provide a vapor tight joint. These collars or rings are inclined downwardly towards the axis of the column for the purpose more fully hereinafter disclosed.

The vane assembly or units 22 are detachably supported from each of the adjacent collars 38 by three equally spaced apart hangers 40. The upper ends of each of the hangers 40 are provided with angularly disposed threaded apertured ears 42 through which a machine screw 44 secures the hanger to the collar 36. The lower end of each of the hangers 40 is provided with an inwardly and angularly disposed projection 46 which is adapted to engage the lower edge of the ring 34 for supporting the vane assembly or unit thereon. Formed integrally with each of the hangers 40 is an inwardly projecting lug 48. The lug 48 is spaced upwardly from the projection 46 so as to form a recess 50 for the reception of the outer edge of the ring 34 to thereby lock the ring and the vane assembly or unit in position on the hangers.

In order to remove the top one of the units 22, the machine screw 44 is loosened and one of the hangers is revolved through an angular magnitude of ninety degrees about the axis of the screw, thereby releasing the ring from one of the hangers and by merely shifting the unit 22 laterally from the recesses of the other two hangers, the hook rod placed into the eye 36 may readily lift the unit from the column for the purpose of cleaning, repairing or replacing the individual unit.

Positioned above the topmost unit 22 is a liquid supply pipe 52 which extends through the cylindrical casing and is provided on the inner ends with a right angle elbow 54 for discharging the liquid onto the disc 24 of the topmost vane assembly 22.

In the operation of the device, the upwardly moving vapors or gases traverse the tubular column in a spiral, rotating and circuitous movement caused by the spirally arranged vanes 26, the annular collars 38 and rings 34. These vapors and gases, as a result of these vane formations, move outwardly towards the periphery of the vane assemblies and are further dispersed by the annular ring 34, some of which are discharged into the annular space surrounding the periphery of the vane assemblies and the inner wall of the column. The descending liquid discharged upon the first disc 24 is dispersed in the form of a spray by the spirally arranged vanes of the assembly unit and by the centrifugal action of the descending spray, further agitation and dispersion takes place when portions of this liquid strike the annular ring 34 and discharge a portion of the liquid into the annular space between the cylindrical wall and the periphery of the vane assemblies. From this point a portion of the liquid is deflected inwardly by the next succeeding collar 38 so as to thereby develop a more intimate interaction and com-

mingling between the descending liquids and the rising vapor of gases and thereby contributes to more efficient operation of the device.

From the above description it will be obvious that the annular rings 34 secured to the lower outer edges of the vane assemblies perform the double function of not only securing a greater dispersion of the downwardly flowing liquid, but also serves to rigidly secure the vanes together so as to prevent their displacement both in the operation of the device and in the removal of the units for cleaning or repair.

It will be further understood that by providing means for detachably securing the vane assemblies or units and suspending them from the spaced apart annular collars 38, these units may be readily removed for cleaning or repair. It will be noted that by providing the locking lugs 48 on each of the hangers 40, these vane assemblies may be locked in position for shipment of the device as a whole.

While in the above specification I have described one embodiment which my invention may assume in practice, it will, of course, be understood that the same is capable of modification and that modification may be made without departing from the spirit and scope of the invention as expressed in the following claims.

What I claim as my invention and desire to secure by Letters Patent is:

1. A fractionating column or the like comprising a cylindrical casing, a plurality of detachable vane assemblies each of which includes a centrally disposed disc and plurality of spirally arranged vanes secured to said disc, each of said vanes overlapping horizontally the next adjacent vane, a ring secured to the lower portion of and adjacent the outer ends of said vanes, said vane assemblies being axially aligned with respect to one another and spaced from the cylindrical wall of said casing, annular collars secured to the inner wall of said casing, and means for suspending each of said vane assemblies from the adjacent collar.

2. A fractionating column or the like as defined in claim 1 in which means are provided for detachably securing said assemblies to said collars.

3. A fractionating column or the like comprising a cylindrical casing, a plurality of removable vane assemblies, each of which includes a plurality of spirally arranged vanes having each vane overlapping horizontally the next adjacent vane, said vane assemblies being axially aligned with respect to one another and spaced from the cylindrical wall of said casing, annular collars secured to the inner wall of said casing, circular rings secured to the lower portion of said vanes, and displaceable means for suspending each of said vane assemblies from the adjacent collar.

4. A fractionating column or the like comprising a cylindrical casing, a plurality of removable vane assemblies, each of which includes a plurality of spirally arranged vanes having each vane overlapping the next adjacent vane, a disc secured to the upper inner ends of said vanes, and a ring secured to the lower ends of said vanes, said vane assemblies being axially aligned with respect to one another and spaced from the cylindrical wall of said casing, an annular collar secured to the inner wall of said casing above each of said discs, respectively, and swingable means for suspending each of said vane assemblies from the adjacent collar.

5. A fractionating column or the like comprising a cylindrical casing, a plurality of removable

vane assemblies, each of which includes a plurality of spirally arranged vanes having each vane overlapping horizontally the next adjacent vane, a disc secured to the upper inner ends of said vanes, and a ring secured to the lower outer ends of said vanes, said vane assemblies being axially aligned with respect to one another and spaced from the cylindrical wall of said casing, an annular collar secured to the inner wall of said casing above each of said rings, and depending hangers for suspending each of said vane assemblies from the adjacent collar.

6. A fractionating device comprising a cylindrical casing having vertically spaced apart annular collars secured to the inner wall of said casing, detachable vane assemblies or units suspended from said collars, each of said vane assemblies including a plurality of dihedral vane members radially disposed from the center of the casing and having outer ends spaced from the inner cylindrical wall of said casing, and means for suspending each of said vane assemblies below and from its adjacent collar.

7. A fractionating device comprising a cylindrical casing having vertically spaced apart annular collars secured to the inner wall of said casing, detachable vane assemblies or units suspended from and wholly below said collars, each of said vane assemblies including a plurality of dihedral vane members radially disposed from the center of the casing and having outer ends

spaced from the inner cylindrical wall of said casing, means for suspending each of said vane assemblies from its adjacent collar, and means carried by said first named means for preventing the displacement of said vane assemblies from said casing.

5 8. A fractionating device comprising a cylindrical casing having vertically spaced apart annular collars secured to the inner wall of said casing, detachable vane assemblies or units suspended from and located wholly below said collars, each of said vane assemblies including a plurality of dihedral vane members radially disposed from the center of the casing and having outer ends spaced from the inner cylindrical wall of said casing, and equally spaced apart hangers secured to said collars and detachably connected to said vane assemblies for supporting said assemblies in position.
